UNITED STATES PATENT OFFICE.

JOHN GELL, OF LONDON, ENGLAND.

TELEGRAPHIC SYSTEM.

1,074,170.

Specification of Letters Patent.

Patented Sept. 30, 1913.

Application filed December 21, 1910, Serial No. 598,557. Renewed February 21, 1913. Serial No. 750,041.

To all whom it may concern:

Be it known that I, JOHN GELL, a subject of the King of Great Britain, residing at London, England, have invented certain new and useful Improvements in Telegraphic Systems, of which the following is a specification.

The object of the present invention is to provide telegraphic exchanges to enable 10 subscribers thereto to communicate with each other directly telegraphically, thus securing a permanent record of the communications and, at the same time, economizing in wires, time and effort by means of my 15 special devices over the ordinary method of telegraphing.

The invention consists in the features and combination and arrangement of parts hereinafter described and particularly pointed 20 out in the claims.

In the accompanying drawings: Figure 1 represents a telegraphic exchange with the operator's signaling set and one set of translators; Fig. 2 shows a direct connection 25 at the local exchange between one subscriber and the other; Fig. 3 represents the perforated tape; Fig. 4 represents a connection between two subscribers in distant towns.

30 In Fig. 1 I show within the heavy lines a switch board having a capacity for nine subscribers. 10 represents a non-polarized indicator, one for each subscriber. Wire from each indicator is carried to corresponding jack switch 11, the spring 12 of which normally rests against earth contact 13, as shown in Fig. 2. 14 represents jack switches which are all permanently connected to the exchange operator's signaling set shown at 35 the right of Fig. 1. 15 represents jack switches connected in pairs to the translating sets, one of which is shown at the left of Fig. 1. 16 represents a double current hand signaling Morse telegraph key of the 40 exchange operator's signaling set. 17 represents the galvanometer, 18 the relay, 19 the sounder, 20 the local battery, 21 the signaling battery. Referring to the translating set, 22 and 22' represent non-polarized 45 electro-magnetic switches arranged to work sluggishly. 23 and 23' represent translating relays. 24 and 24' represent the smaller translating batteries. 25 and 25' represent the larger translating batteries. 26 represents 50 trunk line jack switch connections. 26' represents trunk line indicators. Each

subscriber is supplied with a Gell keyboard perforator 27, represented conventionally in Fig. 2, such as described in Letters Patent of the United States 751,164, February 2, 60 1904, and in an application filed by me Jan. 9, 1911, #601,751, a transmitter 28 as described in United States Patents 890,042, June 9, 1908, and 835,751, November 13, 1906, and in an application filed by me Jan. 20, 1911, #604,487, and a receiver 29 of the same form as that disclosed in application for Letters Patent of the United States filed by me Jan. 30, 1911, #605,655, a galvanometer 30, a two-way switch 31, and a line connecting to its particular jack switch 32 annunciator in the local exchange. Let us assume, in the first place, that a subscriber #3 requires to make connection with another subscriber #1 both of whom are connected 70 to the same exchange. The procedure would be as follows: Subscriber #3, having perforated the message to be sent, moves his switch to the transmitter connection, thereby sending a current from the battery of 80 subscriber #3 set shown at the right of Fig. 2, and connected to contacts 36 and 37, through the special indicator at the exchange and drawing the attention of the exchange operator to the call. The jockey 85 roller X acting on the beveled end of key lever 33 keeps the said transmitter key 33, when at rest, in contact with one or the other of the contact points at its ends. The exchange operator would take a cord and 90 connect jack switch 14 to the jack switch 11 of the subscriber. The insertion of the plug into the jack switch will disconnect the subscriber's line from earth and connect this line through the cord to the exchange 95 operator's set of instruments. The galvanometer in the subscriber's office would indicate this movement on the part of the exchange clerk; the subscriber would start the motor of the transmitter, and send the request to be put through to subscriber #1. The exchange operator would then take the 100 plug from jack switch 14 and place it in subscriber #1's jack switch 11. The connection is shown completed in Fig. 2. Having obtained connection, subscriber #3 now starts the transmitter and sends the perforated tape 32 through it. This tape, represented in Fig. 3, has a series of arbitrary holes perforated in it, which control the 110 movements of the transmitting pins in transmitter 28. The movements of this pair

of transmitting pins in turn control the movement of main transmitting key 33, and auxiliary transmitting key 34 connected to and insulated from the main key 33 which oscillates on pivot 35. 36 represents a block connected to the copper pole of the subscriber's battery. 37 represents a block connected to the zinc pole of the subscriber's battery; 38 and 38' contact screws in connection with main key 33; 39 and 39' contact screws in connection with auxiliary key lever 34. In Fig. 3 the central line of holes represent feed holes, and which are used in the perforator and the transmitter in connection with star feed wheels to actuate the movement of the tape. The upper row of holes is termed "marking holes", the lower holes "spacing holes". One of the transmitting pins termed the "marking transmitting pin" oscillates underneath the tape and in a line with the marking holes. In a similar manner the spacing transmitting pin is in a line with the spacing holes. The tape is carried over the upper ends of these transmitting pins. The transmitting pins are pressed downward by the movements of the cam in unison with the forward movement of the tape, and permitted to rise under the influence of springs in such a manner that when a marking transmitting pin rises against the plain tape, there is no movement of the transmitting key, but if a marking transmitting pin, when it rises upward, passes through a hole in the tape, it causes key 33 to touch contact 38 and send a positive current through the subscriber's wire, indicator 10, switch, plug cord, corresponding plug, switch and indicator of subscriber #1 through subscriber #1's galvanometer, switch, receiver, to earth. In passing through receiver coils 40 and 40', it causes cores 41 and 41' to become magnetized; these, in turn, actuate polarized armatures 42 and 42' connected with main shaft 43. Shaft 43 is pivoted in such a manner that armatures 42 can oscillate between magnets 41 and 41'. Fixed to the same shaft 43 is a bracket arm carrying a subsidiary shaft upon which the marking wheel 44 is fixed. The marking wheel 44 is rotated by the mechanism of the receiver, and receives a supply of ink from an inking disk. The marking current received from subscriber #3's transmitter causes the marking wheel 44 to touch the moving receiving tape 45 and impress upon it an ink mark. At the same moment that the positive current has traveled to the distant subscriber, auxiliary key 34 has closed circuit with contact 39', permitting the negative current of subscriber #3's battery to flow to earth. In like manner, when a spacing transmitting pin passes through a spacing hole in the perforated tape, key 33 closes circuit with 38', 34 closes circuit with 39, and negative

current is sent to subscriber #1 and the positive current to earth. This negative current, acting on the tongues of the armatures in receiver 29, causes the inking disk to be moved away from the receiving tape 70 45. When the marking and the spacing holes are vertically in a line, the marking disk 44 touches the tape 45 momentarily, because the positive and negative currents succeed each other rapidly, but when the 75 holes on the perforated tape are diagonal, an interval of time elapses between the marking disk 44, touching the receiver slip 45 before it is removed therefrom, and a dash is the result. When subscriber #3 80 has completed the transmission of the message, he moves his switch to the receiver contact, subscriber #1 sends the acknowledging signal, and switches back to his receiver contact and the apparatus assumes 85 normal position.

In the event of the connection being required between two distant towns, it is essential that there be means of reinforcing the current so that it shall be sufficient to 90 actuate the receiving instrument in a distant city. At the same time, it is essential that these currents should be of such a strength that while on the one hand the one current is sufficient to actuate the mechanism in the distant exchange, the current that is received at the distant subscriber's office shall be of the same strength as though a local connection had been made, so that whether the connection is a local one or 95 from a distance, the subscriber's instrument will be similarly affected, and the adjustment maintained normally.

In Fig. 4 I have represented a diagram of the exchange in Washington and New 100 York, and the connections made on Fig. 1 bringing in the translating set of reinforced batteries. When the Washington subscriber asks for the New York subscriber, the Washington switch board attendant gets through 110 to the New York subscriber through the New York exchange, but instead of using a plain cord with a plug at each end as for a local connection just described, he takes a cord and connects switch 15', Fig. 1, to the 115 jack switch 11 of the Washington subscriber, and takes a cord from 15 and connects the other end to the New York trunk line jack switch 26. When the subscriber in Washington is through to the subscriber in New 120 York, the same procedure takes place as though he were connected locally, as previously described, but in this case the current from the Washington subscriber, after entering the Washington exchange, passes from 125 the cord connecting his jack switch to the translating set in the following manner: It passes through lever 46, contact 47, through non-polarized electro-magnetic switch 22' through translating relay 23' to earth. In

passing through translating relay 23' it causes tongue piece 48' to close circuit with contact 49. This causes the positive current from main battery 25 to traverse through 5 contact 49, tongue piece 48', switch contact 51' through lever 46', cord, jack switch 15 and jack switch 26 onto the trunk line to New York. On reaching New York (see at right of Fig. 4) the current passes through 10 lever 46', contact 47', switch 22, relay 23 to earth. In doing so, it closes circuit as follows: contact 49, lever 48, through contact 51, lever 46 through New York subscriber's jack switch 11 and onto the New York subscriber's receiving instrument, actuating it 15 in the manner as previously described, but from the small battery 24, 24' of the translating set, and the translating sets are so arranged that batteries 24 and 24' are of the same electro-motive force as the battery in 20 each of the subscriber's stations, and battery 25 and 25' are of sufficient strength to carry the communication to all offices within a large zone. By the use therefore of the battery 24, 24' at the exchanges and which are 25 relayed into use when distant subscribers are connected, the instruments in the subscribers' stations will be worked by a current of the same strength for long distance service 30 as for local service. We have hitherto dealt with communications in a zonal district of approximately one thousand miles square, but there is a further development as in the case of a communication from Washington 35 to San Francisco. In this case, the communication would be translated at Chicago and Denver. Both Chicago and Denver would require translating sets similar to those described, but with large batteries on both 40 sides instead of a large and small battery, as shown in Fig. 4.

On the switchboard the indicators 10 are not shown in conventional form, but are represented as in the form of a disk showing 45 through six segmental openings. The disk is so painted that under the influence of a spring or weight the black segments come opposite the openings, but when a current flows through it the white segments disclose 50 themselves, and indicate the same to the exchange operator.

In connection with the receiver there is a bell actuated by the incoming current, and means by which the incoming current may 55 be used to start the receiving instrument.

Referring to the exchange operator's signaling set: in Fig. 1 at 16 is represented diagrammatically a double current Morse key with a switch which enables the operator to 60 place the key either in a position for receiv-

ing or sending. Normally the key is in the receiving position, which enables incoming signals to pass through the key and then through the receiving apparatus to earth. When the exchange clerk has received a call, 65 he turns the key-switch to the sending position. This at once sends a current to line of one polarity and the other current of the battery to earth. When the Morse key is depressed, the reverse takes place, and the current of opposite sign is sent to line, so that when the key-lever is actuated reversals are sent through to the subscriber which actuate the armature of his receiving instrument, and give the required signals. The connections are so arranged that when the key is at rest and the key-switch in the sending position, the outgoing current so actuates the receiving instrument that the marking wheel is kept from the receiving tape. 70 75 80

I claim:—

1. A telegraphic system comprising exchanges, trunk line connections between said exchanges, local subscribers' connections at each exchange, transmitting and receiving instruments at each subscriber's station, translating sets at each exchange, each set including a large and small battery and a relay for connecting the large battery with the trunk line at the sending station, and a 85 relay for connecting the small battery with the local line at the receiving station, and batteries at the subscriber's station corresponding substantially in current intensity 90 to the small batteries. 95

2. A telegraphic system comprising exchanges, trunk line connections between said exchanges, local subscribers' connections at each exchange, transmitting and receiving instruments at each subscriber's station, translating sets at each exchange, each set including a large and small battery, and a relay for connecting the large battery with the trunk line at the sending station, and a relay for connecting the small battery with the local line at the receiving station, electro-magnetic switches controlling the relays of the large and small batteries of the translating sets, said switches having sluggish magnets to maintain contact and be unaffected by the more rapid alternations of current from the relays, substantially as described. 100 105 110

In testimony whereof, I affix my signature in presence of two witnesses.

JOHN GELL.

Witnesses:

EDWARD N. SAITA,
EDWIN S. CLARKSON.
